SCREW PUMP

Application filed June 7, 1929. Serial No. 369,037.

This invention relates to rotary pumps, metering devices, or hydraulic motors of that type in which a smaller externally threaded worm rotates and revolves eccentrically inside a larger internally threaded casing, the threads of the two intermeshing and the space between them being filled by a cylindrical rotor fitting the inside of the casing and having an eccentric cylindrical bore in which the worm fits and rotates. If the threads are formed and the parts fitted so as substantially to prevent leakage between them, and the rotor with its included worm be rotated, the device will act as a pump or metering device to pass fluid along the spaces between the threads of worm and casing from one end to the other; or if fluid under pressure be supplied at one end, it will act as a hydraulic motor or metering device, causing the worm and rotor to rotate inside the casing as the fluid passes through.

Such devices have been known for some time, but have not been practical, as the best forms or contours heretofore known for the intermeshing threads have been such as would wear rapidly and lead to excessive leakage, and also, by reason of their undercut form, have been difficult to produce with the required accuracy. The characteristic feature of this invention resides in certain forms or contours for the intermeshing threads which need not be undercut, are easy to produce with the required accuracy, and are not subject to rapid wear or leakage.

In the accompanying drawings, Fig. 1 shows longitudinal and transverse sections through a pump according to the present invention on planes AA and CC respectively, and Fig. 2 is a diagrammatic transverse section on either plane CC or DD of Fig. 1, showing the outlines to a larger scale. Figs. 3 and 4 represent transverse sections of threads suitable for pumps according to the present invention, which have contours based on what is known as the cycloidal system,

and Figs. 5 and 6 represent similar threads having contours based on what is known as the circular or "pin-tooth" system. Fig. 7 represents a series of four cross sections, by planes parallel to the axis, of one thread derived by twisting to an unusually great helical angle the tooth-form of Fig. 4.

In Fig. 1 the numerals 1, 3, 5, represent the spaces between threads of the screw formed in the stationary casing 7. Numerals 2, 4, 6, 55 represent the spaces between threads of the smaller externally threaded worm 8 which rolls around inside the casing 7. The space between 7 and 8 is filled by the cylindrical rotor 9 fitting the inside of the casing 7 and having the cylindrical bore 10 in which worm 8 fits and rotates.

The ends of the casing 7 are closed by the heads 16, 17, the former of which has a packing gland 18 to prevent leakage of liquid 65 around the drive-shaft 19. This drive-shaft passes through the head 16 and is connected to the end of the rotor 9 in any suitable manner so that shaft and rotor will turn together. In the drawings (Fig. 1) this connection is 70 indicated as being a coupling 20 of the well-known "Oldham" type, operating between the flange 21, which is integral with shaft 19, and the end of rotor 9, so that slight differences in alignment between shaft and rotor 75 will not cause any binding. The outer end of shaft 19 may be supported and driven by any means desired.

The rotor 9 is held, endwise, by head 16 through flange 21 and coupling 20, on one end, 80 and directly by head 17 on the other end. The worm 8 is held in position endwise by two flanges 22 and 23, formed integrally with it, which roll against the insides of heads 16 and 17, in a manner similar to the flange of 85 a car wheel. Thus all end-pressure on rotor and worm is transmitted to one of the heads, 16 or 17.

The space 3 in the casing (either empty or filled with liquid) extends helically around 90

inside the casing from position 11, where it is stopped off by a thread of the worm, to position 15, where it is stopped off by another thread of the worm. Likewise space 4 in the worm extends helically around from position 12 to position 14, at both of which it is stopped off by threads of the casing. If these stoppages at 11 to 15 are tight, so that no liquid leaks past them, the pump will 10 deliver the full volumetric content of its spaces at each revolution. If they are not made tight or do not remain so, then the pump will be correspondingly inefficient.

The forms of the threads are for simplicity shown in Fig. 1 as rectangular, but they cannot actually be as simple as this, for interferences between them would result at every section between OE and OF, Fig. 2, except on the central section OB. To prevent this, 15 clearances between them must be allowed at certain points in certain amounts, and to allow this while still retaining tightness, requires thread contours of certain special shapes, now to be described:

25 For the worm and internal screw to roll together, they must bear to each other the relation of single (or multiple) to multiple-threaded screws of the same helical angle. Practically, the best relation is that of a single-threaded worm to a double threaded internal screw, as illustrated in Figs. 1 and 2. For such a pair of screws there may be found two tangent circles GFJE and OLJM, whose diameters bear the ratio of 2:1, the smaller 30 circle passing through the center, O, of the larger. As the worm rolls around inside the internal screw, the circle OLJM moves in perfect rolling contact with circle GFJE. These may, therefore, be considered as the 35 pitch circles of the worm and screw. The threads may lie entirely inside the pitch circle, or entirely outside, or partly inside and partly outside as shown. Then the interaction of the threads of the worm and internal screw is the same as that of the teeth 40 of a pair of internal twisted gears of unusually great helical angle. Any forms of gear tooth contours which would work properly together under these conditions would give, by twisting to the desired helical angle, 45 screw-thread contours that would work properly together without interference. Some of them would possess the property of tightness to liquids required for such a screw pump as shown here, but others would not.

50 There are several systems of contours used for gear teeth, such as the radial-flank system, the involute system, the cycloidal system, and the circular or so-called pin-tooth system. Up to this time the only one of these applied to screw-pumps of this type has been the radial-flank system. In this system the threads have been entirely inside the pitch circles; the teeth, or threads, of the internal 55 screw then have had straight, radial flanks;

and the threads of the worm are formed to work properly with them. This requires that the threads of the worm be grooved out or undercut.

For this type of tooth, the "outside diameter" of the internal screw thread must be just twice that of the worm. This combination in such a pump forms the subject of a U. S. Patent, #1,490,876, issued to J. K. Werner, April 15th, 1924.

Theoretically, threads of this type would be liquid-tight, but those contacts which do the sealing are sharp corners, like knife-edges, and rub against flat surfaces. The sharp corners of contacts like these will very 75 soon wear off round and allow leakage. Moreover, the undercut curved form of contour, which must be very accurately fitted if tightness is to be secured, is not only difficult to make but especially difficult to make accurately. Hence, threads like those based on the radial-flank internal gear tooth are not practical for service. These, however, constitute the state of the art covering pumps of this type prior to the invention herein 80 claimed.

85 As before mentioned, Figs. 3 and 4 show two tooth-forms of different proportions based on the cycloidal system, and Figs. 5 and 6 show two tooth-forms based on the circular system, and Fig. 7 shows a series of four cross sections of one worm thread and screw space derived by twisting from the tooth-form of Fig. 4, these sections being made by planes OB, ON₁, ON₂, and OE of Fig. 4, respectively. Similar series of cross sections could be 90 made for all the tooth-forms of Figs. 3 to 6, but the additional ones would be so similar to those of Fig. 7 in all but unimportant details and proportions that they are not shown.

95 All the forms shown in Figs. 3 to 7 have a common property: The contacts between the surfaces of the worm and internal screw are tangent surfaces presenting good wearing contacts, like well-designed gear teeth, instead of sharp-edged contacts as in the radial-flank system. They differ also from that form in that the teeth, or threads, lie partly 100 outside of the pitch circles, so that the ratio of the outside diameters is no longer 2:1. In Fig. 3 it is 7:4, or 1.75:1; in Figs. 4 and 6 it is 29:17, or 1.706:1; in Fig. 5 it is 9:5, or 1.8:1; and other proportions might be used.

105 In all these diagrams Figs. 3 to 6, O is the center of the internal screw, which has its pitch circle JGE described about O; and K is the center of the worm, which has its pitch circle JMO described about K. The path of contact between the teeth of the two is ZJCDH.

110 In Figs. 3 and 4, on the cycloidal system, the tooth-contours are generated by the internal generating circle IZ'JZ'', having its center at V, and the external generating circle JY having its center at W. If (as shown

in these diagrams) the sum of the radii of these two circles, VJ plus JW, equals the radius JK of the pitch circle of the worm, then, as is well known to those familiar with the theory of gears, there is also an intermediate describing circle JCDH, having its center at X, such that XK equals KV equals JW.

The internal circle IZ'JZ'' generates the flank JQ of the worm contour and the face JP' of the internal screw contour, which maintain tangential contact with each other to the right of J along contact circle IJZ'', from point J to a point Z, not shown, where circle IJZ'', extended, intersects circle HZ'P, extended. At these points, J and Z, this particular tangential contact terminates. In like manner the external circle JY generates the flank JT of the internal screw and the face JF of the worm, which maintain tangential contact with each other to the left of J along contact circle JY from J to Y, at which points this contact terminates. Furthermore, the face JP' and face JF are again generated by intermediate circle JCDH and these faces maintain tangential contact with each other to the left of J along contact circle JCDH from J to H, at which points this contact terminates. In addition to these three tangential contacts there are the following non-tangential contacts. The corner of the internal screw tooth, P', maintains non-tangential contact, as at S in Figs. 3 to 6, with the root of the worm tooth, which is shaped to conform, in the curve QR which forms a fillet at the base of the worm tooth. This non-tangential contact extends along circle HZ'P from point P on the center line toward the right, to point Z, not shown, but mentioned above. This latter point, as already seen, is also the terminus of the tangential contact JZ''Z. Also the corner of the worm tooth H' maintains exactly similar non-tangential contact with the root of the internal screw thread, the latter being shaped to conform in the curve TT' which forms a fillet at the base of the internal screw tooth. This non-tangential contact extends along circle FUYH from point U, on the center line, to point Y, which latter point is also a terminus of the tangential contact JY.

If an internal gear and pinion made on this system be rotated together in clockwise direction about their centers O and K, their teeth will first come in contact at the point Z (not shown) to the right of Z'' on circle IZ'JZ'', and will remain in contact until they reach point H. There will be continuous tangential contact along curves ZZ''J, JCDH and JY. From J to C and Y there will be double tangential contact, as shown at C and Y. There will be continuous non-tangential contacts from Z to P and from U to Y.

Every tooth must have two sides, only one of which is indicated here. For the other

side, similar contacts would result, except that they would be reversed, right and left, about the center line XW. If such an internal gear and pinion be twisted uniformly to give an internal screw and worm similar to Fig. 1, the two sides of any mating gear-tooth and space will twist into the two sides of a mating screw thread and space, and their successive transverse sections will give continuous contact between the helical surfaces of the screw worm, all along the curves ZJ, JCDH, JY, ZP and UY on one side, and also along the corresponding (left handed) curves for the other side. If, for example, the twisting be such as to produce "right handed" screw threads (in which for clockwise rotation successive sections move away from the observer), then the contours shown in Figs. 3 and 4 would produce the nearer side of a mating worm thread and internal screw space; while the corresponding "left handed" contours would produce the farther side.

This has been indicated in Fig. 2, where the broken-line curves JH, JY and JZ, indicate the lines of tangential contact and lines ZP and YU indicate lines of non-tangential contact for the nearer side of a worm thread and internal gear space, and the dotted-line curves JH', JY', JZ' and lines Z'P, Y'U, indicate those for the farther side.

The continuous and tangential nature of these contacts is further indicated in Fig. 7. As already stated, this shows a series of four cross sections of one worm thread and screw space derived, by twisting from the tooth-form of Fig. 4, these sections being made respectively by planes OB, ON₁, ON₂, and OE. All these planes pass through the center line, O, of the internal screw, and hence the shape of these cross sections, so far as the internal screw is concerned, will be the same in all of them. But only plane OB passes through the center line K of the worm. The other planes cut this worm at successively greater distances from its axis. Hence the sections of worm thread made by these planes will all be unlike.

In Fig. 7, the cross section of internal screw space, alike for all four planes, is P₂, J₂, B₂, B₁, J₁, P₁.

The four cross sections of worm threads made by these four planes are as follows:

Plane, in Fig. 4	Section of worm thread, Fig. 7
OB	R ₂ Q ₂ J ₂ U ₂ U ₁ J ₁ Q ₁ R ₁
ON ₁	R ₄ Y ₄ U ₄ U ₃ Y ₃ R ₃
ON ₂	R ₆ U ₆ U ₅ D R ₅
OE	R ₈ U ₈ U ₇ R ₇

The right hand side of Fig. 7 corresponds to the nearer side of a right-handed worm thread and screw space twisted from the tooth contours of Fig. 4, and the left hand side of Fig. 7 corresponds to the farther side of such a thread.

The apparent skewing of the worm thread sections in Fig. 7 is due to the section planes cutting that thread at successively greater obliquities. There is, of course, no change 5 in the actual shape of the thread.

As the sectioning plane swings to the left in Fig. 4, passing from OB through ON₁, ON₂, and all intermediate positions successively to OE, the worm thread is shown in

10 Fig. 7 to lift out of the internal screw space.

As it does so, the sides of the worm thread are seen to maintain contact with the sides of the internal screw space in a continuous and tangential manner. On the left hand side

15 they do this for a time only, after which contact on this side disappears, but on the right hand side contact is fully maintained until the worm thread is all the way out. Starting with section by plane OB, there is contact

20 on the left at J, and on the right at J₁ (corresponding to J in Figs. 2 and 4). As the section-plane moves through its successive positions to OE, contact on the left moves

25 up through Y, to point P₂ (corresponding to point Z of Figs. 2 and 4), after which there

is an opening to the right of P₂. But on the right hand side of Fig. 7 the contact first becomes double, passing from J, down to Y (see Figs. 2 and 4) and up to Y₁. After that

30 single contact obtains, passing upward through D to P₁, (corresponding to point H of Figs. 2 and 4), where the worm thread is fully out of the internal screw.

The above contacts were all tangential.

35 There is also a continuous non-tangential contact at the left between corner P₂ and fillet curve R₂Y₂, as at point S of the worm tooth. This non-tangential contact S lasts until tan-

40 gential contact Y₁ has moved up to corner P₂, when both of them disappear. There is also a continuous non-tangential contact at the right between worm tooth corner and the fillet curve from B₁ to Y. This lasts while the worm tooth corner is moving up from U₁

45 to U₂.

The character and extent of these tangential and non-tangential contacts between the surfaces of worm and internal screw, as shown in Figs. 2, 4, and 7, has now been made plain.

50 It remains to show how they close off the successive spaces of the pump from each other.

In Fig. 1, section C C cuts through spaces 3, 4 and 13. At the latter, the worm thread

55 meshes into the internal screw space and separates internal screw space 1 (coming down helically around the front) from space 5 (going up helically around the back), section C C cuts these parts of spaces 1 and 5 also.

If the diagrammatic cross section in Fig.

60 2 be ascribed to section C C of Fig. 1, then it will show these spaces. They are marked with a sub-script "c" to indicate that they belong to section C C of Fig. 1. They are:

space 3, at the top of the internal screw, space

65 4_c at top of worm, spaces 1_c and 5_c at left and

right of center line, and 13_c at the bottom. Here the worm thread fits down into the internal screw space and the two are in close, tangential contact, on the nearer side along line HJY, then across the bottom on line U, 70 from U₁ to U₂ of Fig. 7, and then on the farther side along the line Y¹JH¹. These would effectually shut off space 1_c on the left from space 5_c on the right, were it not that from Y to U₁ on the nearer side and from U₂ to Y¹ on the farther side of the contact is 75 not tangential and there is a possibility of slight leakage.

On the nearer side, liquid from space 1_c could pass under the edge Y of Fig. 2 (which is line U₁ U₂ of Fig. 7), up around the non-tangential contact edge YU (YU₁ in Fig. 7), around through the thin space between the line YU and contact line YJ to line JU of Fig. 2 (which is the narrow triangular space 80 J₁ B₁ U₁ in Fig. 7), and so on through to the right into space 5_c. This will be called "leakage a".

On the farther side there would be an exactly similar and equal leakage from space 90 1_c through the narrow triangular space J₁ B₁ U₂ of Fig. 7, down around the edge U₂ Y₁, under Y₁, and so on into space 5_c. This will be called "leakage b".

Again, in Fig. 1, section D D cuts through space 12. Here the internal screw thread meshes up into the worm space and separates worm space 2 (coming down around the front) from space 4 (going up around the back). Section D D cuts these parts of spaces 95 2 and 4 also.

If the diagrammatic cross section in Fig. 2 be now ascribed to section D D of Fig. 1, then it will show these spaces. To differentiate them from the ones previously considered they are marked with a subscript "d". They are: space 2_d at the left, space 4_d at the right, and 12_d at the bottom. Here the internal screw thread fits up into the worm space and the two are in close tangential contact, on the nearer side along line JZ, on the farther side along line JZ¹, and across the top on line P, from P₂ to P₁ of Fig. 7.

110 There are here two possibilities of slight leakage from space 2_d to space 4_d. On the nearer side of space 12, liquid from space 2_d could pass down around the non-tangential contact edge Z¹ P (P² in Fig. 7), around through the thin space between the line Z¹ P and contact line Z¹ J to line P₁, Fig. 2, (which is the narrow space P₂ Q₂ J₂ in Fig. 7), and so on into space 4_d. This will be 115 called "leakage c".

On the farther side of space 12 there would be an exactly similar leakage from space 2_d through the narrow space similar to P₁ Q₁ J₁ of Fig. 7, up around the edge PZ, and so on into space 4_d. This will be called "leakage d".

120 Fig. 7 represents spaces 12, 13, and part 130

of 14, of Fig. 1. At space 12, the internal screw thread separates worm space 2, coming down helically from the left, around the front, and worm space 4, going up helically around the back, to the right. At space 13, the worm thread separates internal screw spaces 1 and 5 as already described. At space 14, the internal screw thread separates worm spaces 4 and 6 in a manner similar to that at space 12. Then it is seen that, at the left, spaces 2 and 1 are in full and open communication through the opening to the right of edge P_2 . This in Fig. 2 is all along the line $Z'H$ at the farther side.

15 Similarly, of course, if spaces 1 and 2 are in free communication with each other, so will be spaces 3 and 4, and likewise 5 and 6, of Fig. 1.

At the right, in Fig. 7, it is seen that space 4 is always separated from space 1 by the close tangential contact, as at J_1 , Y_3 , D , and P_1 , etc., which is the same as contact line JH at nearer side in Fig. 2. There is no leakage path here.

25 To recapitulate: Spaces 1 and 2 are in free communication and form one space; similarly with spaces 3 and 4, and with spaces 5 and 6. There is no communication or leakage path from space 1 to space 4, nor (similarly) from space 3 to space 6. Space 1 is shut off from space 5, on the nearer side, by the tangential contacts along lines HJ and JY and the non-tangential contact along line YU ; by the tangential contact across the bottom at U and on the farther side by non-tangential contact UY' , and tangential contacts $Y'J$ and JH' . There is possibility of a slight leakage (a) past non-tangential contact YU and (b) past non-tangential contact UY' .

Space 2 is shut off from space 4 and, in similar manner, space 4 from space 6 on the nearer side by tangential contacts on lines HJ and JZ and non-tangential contact ZP ; 45 across the top at P and on the farther side on non-tangential contact PZ' and tangential contacts $Z'J$ and JH' . There is possibility of a slight leakage (c) past non-tangential contact ZP and (d) past non-tangential contact PZ' .

These four possibilities of leakage, a, b, c, d, from space 1 to space 5 and from space 2 to space 4, due to the non-tangential nature of contacts on edges YU , UY' , $Z'P$ and PZ are, 55 however, very small. Even if the corners at roots of worm and screw teeth were sharp reentrant corners entirely unfiled, the openings of these edges would be very small. Taking as unit area the total combined area 60 of space 12 plus space 13 (which is depth of thread $\times$ pitch of single thread and space) such measurements and computations from Fig. 4 yield the result that this combined leakage cross-section past corners if unfiled 65 would equal only 0.0028 of the combined

working cross-section of the threads, or less than $\frac{3}{10}$ of 1%.

With filleted corners giving continuous contacts, even though sharp-edged ones, this leakage is, theoretically, completely stopped. 70 In practice, due to slight inaccuracies and effects of wear there might be slight possibilities of leakages past these corners. However, these contacts have no mechanical work to do. That is all done by the tangential contacts of the tooth faces. The wear on these non-tangential contacts will, therefore, be negligible and they will retain their original tightness for a long time. The possibility of leakages past them is further greatly reduced by the very thin spaces through which such leakages must also pass such as around from YU to JU and from $Z'P$ to PJ , in Fig. 4. Hence the total leakage past these non-tangential contacts will be but a very small 80 fraction of the $\frac{3}{10}$ of 1% mentioned above and is quite insignificant. This is in strong contrast to the effects of wear in non-tangential edges heretofore used, as shown in U. S. Patent 1,490,876 previously referred to. 85

The above discussion has been concerned with the contours of Figs. 4 and 7, but would have been the same for Fig. 3, which is also on the cycloidal system, except that the ratio of leakage to total area might have differed 90 by a small fraction of a percent.

The difference between the contours of Figs. 3 and 4 lies in the proportions of their generating circles. In Fig. 3 these are chosen to give equal height and depth of tooth above 100 and below the pitch circles. This results in giving a slightly undercut pinion tooth, as shown at A, Fig. 3. In Fig. 4 the generating circles have been chosen to give no undercutting at A, and this causes the tooth-depth 105 to be greater outside than inside the pitch circles, which is in no way detrimental.

The contours of Figs. 5 and 6 are generated in a different way, but lead to practically the same results. In these, the working contours of the pinion teeth are circles, such as QJU , struck from centers lying on the pinion pitch circle. One of these centers is shown at W , for the contour circle passing through H . Then the contour of the internal gear 110 teeth outside its pitch circle will also be circles of the same radius as those of the pinion, but struck from points of the pitch circle of the internal gear. Inside its pitch circle, its contours will be straight lines such as JP , tangent to the outside contour circles at points a little outside the pitch circle. 115

Then the path of contact will be a curve (not a circle) $ZJCDH$, which is generated by a point F on a line JXF passing through 120 the point of tangency J of the pitch circles, intersecting the pinion pitch circle in X , and with the distance XF kept constant and equal to the radius WH of the contour circle as X moves around the pitch circle JXM . 125

When the center of the contour circle is at J, the pinion contour circle and the internal gear contour circle will coincide at CY, and when the teeth are twisted into the 5 form of screws this curve CY performs the same functions as did the contact line JY in Figs. 3 and 4: It gives a line of tangent contact between the nearer surfaces of worm and internal screw threads and, in conjunction with contact line JCDH, shuts off space 10 1 (at the left) from space 5 (at the right) down to point Y. With this minor difference, the discussion for Fig. 4 will apply also to Figs. 5 and 6. The difference, if any, in 15 the leakage percentages, would be of a minor order.

The difference between the contours of Figs. 5 and 6 is similar to that between Figs. 3 and 4. In Fig. 5 the radius of contour 20 circle, WH, has been so chosen as to give greater tooth-depth inside than outside the pitch circles, but this leads to slightly undercut pinion teeth, as at A, Fig. 5. In Fig. 6 the radius WH has been so chosen as to give 25 no undercutting at A, but the tooth-depth outside the pitch circles is now greater than that inside, as it was in Fig. 4.

It is evident that other proportions could be used for the pitch circles than those in 30 Figs. 3 and 4, or other radii for the contour circles than those in Figs. 5 and 6, without changing the nature of the result greatly. These might even be so chosen that the teeth would lie either entirely inside or entirely 35 outside the pitch circles, provided the lines of continuous tangential contacts between wearing surfaces were afforded. It is also probable that from the infinite number of tooth contour systems possible, other systems 40 than the cycloidal or the circular types here illustrated could be found that would give substantially the same results. This invention does not reside in a particular kind of tooth or thread contour, but in the application, to this type of screw pump, of any of 45 the forms of tooth contours that will give broad tangential contacts between the wearing surfaces of the threads of the worm and internal screw and maintain substantial 50 liquid-tightness at the barriers that separate their successive spaces.

What I claim is:

1. A screw pump having a threaded screw member eccentrically positioned within and meshing with an internal thread of an enclosing member having an internal diameter relatively greater than the outer diameter of the screw and in which the space between the screw and the internal thread is filled by a rotor member, characterized in this; that the contours of the intermeshing threads are pairs of curves which are the intersection of a longitudinal axial plane with 55 pairs of intermeshing helical surfaces generated by twisting about their respective axes

an internal gear and its intermeshing pinion whose tooth surfaces are of that particular class that make continuous tangential surface contact with each other from their first to their final contacts. 70

2. A pump according to claim 1 characterized in this: That the thread contours are of a form which would result from twisting an internal gear and its intermeshing pinion whose teeth are formed according to the 75 cycloidal system.

3. A pump according to claim 1 characterized in this: That the thread contours are of a form which would result from twisting an internal gear and its pinion whose teeth are 80 formed according to the circular system.

4. A pump according to claim 1 characterized in this: That the outside diameters of the threads of the internal screw and the worm are greater than the diameters of 85 their pitch circles.

5. A pump according to claim 1 characterized by this: That the contours of the intermeshing threads are of a form which would result from twisting an internal gear and 90 its pinion whose pitch circles have diameters in ratio of any two whole numbers.

6. A pump according to claim 1 characterized by this: That the contours of the intermeshing threads are of a form which would result from twisting an internal gear and its intermeshing pinion whose pitch circles have diameters in ratio of any two whole numbers and whose tooth contour outside 95 diameters have a different ratio than their pitch circles. 100

7. A screw pump having a threaded screw member eccentrically positioned within and meshing with an internal thread, of an enclosing member having an internal diameter 105 relatively greater than the outer diameter of the screw and in which the space between the screw and the internal thread is filled by a rotor member, characterized in this: That the contours of the intermeshing threads are 110 of a form which would result from twisting an internal gear and its intermeshing pinion whose pitch circles have diameters in ratio of any two whole numbers and whose tooth contour outside diameters have a different ratio than their pitch circles. 115

8. In a screw pump, metering device, or motor, the combination of an internally threaded member, an externally threaded worm eccentrically arranged within the said internally threaded member, the threads of the two having the same helical angle and intermeshing with each other, a rotor having a cylindrical outer surface fitting the inside of the internally threaded member and having an eccentric cylindrical bore fitting the outside of the worm, the contours of the said intermeshing threads being of a form which would result from twisting an internal gear and its pinion whose pitch circles have 120 125 130

diameters in ratio of 2:1, their teeth being formed on any tooth contour system that provides continuous tangential surface contacts between their wearing surfaces from 5 their initial to their final contact.

9. A pump according to claim 1 further characterized in this that the re-entrant corners of the mating spaces of said gear and pinion are filleted in such a manner that the 10 projecting corners of the gear and pinion teeth make continuous non-tangential contact therewith from their first to final contact.
